MANACLE

Filed Dec. 9, 1929

Fig. 1.

Fig. 2.

UNITED STATES PATENT OFFICE

STELLA FRANCES GILL, OF KANSAS CITY, MISSOURI, ASSIGNOR TO NEWTON S. HILL-YARD, OF ST. JOSEPH, MISSOURI

MANACLE

Application filed December 9, 1929. Serial No. 412,805.

My invention relates to manacles, and has for its principal objects to reduce the time necessary for applying manacles to a prisoner and removing the manacles from the prisoner, to simplify and reduce the cost of making and assembling manacles, to facilitate use of manacles, and to eliminate the possibility that the prisoner may pick the lock of manacles whereby he is fettered.

In accomplishing these and other objects of the invention, I have provided improved details of structure, the preferred forms of which are illustrated in the accompanying drawings, wherein:

Fig. 1 is a perspective view of a pair of manacles in closed position, walls being partly broken away to illustrate the single locking mechanism.

Fig. 2 is a similar view of the manacles in open position.

Referring in detail to the drawings:

The supporting element of the manacles comprise mating plates including body portions 1 and laterally extending integral arms 25 including arcuate inner socket or seat portions 2 and outer seat portions 3 spaced by walls or fingers 4.

The plates are spaced by a recessed block 5 having edges registering with the upper, outer and lower edges of the body portions in the position of the manacles shown in the figures, and riveted to the plates to firmly secure them together. The inner edge of the block is spaced from the inner edge of the body portions to form a channel for the free arcuate finger or end 6 of a lever 7 pivotally mounted on the outer ends of the arms by a pin 8, and freely revolvable between the arms.

The spacing block 5 is provided with a recess 9 to accommodate a latching pawl 10 pivotally mounted on a pin 11 fixed to the plates, and a spring 12 having one end anchored to the block at 13 and the other end engaged with the toothed end 14 of the pawl for urging the pawl outwardly of the recess into the path of the lever finger 6.

The block 5 includes a wall 15 formed by recessing the block and closing the upper edge of the manacles formed by the spaced body portions of the plates, said wall having an end

portion provided with an inclined face 16 adapted to receive the upper edge of the toothed end of the pawl to stop the pawl in lever-latching position.

The block further includes a finger-like inner edge portion 17 having an end spaced from the wall 15 to form an opening through which the toothed end of the pawl projects to engage the lever.

The opposite end 18 of the pawl is formed arcuately to comprise a cam-like finger located to receive the ward of a key inserted through a keyhole 19 in one of the plates whereby the pawl may be moved pivotally away from latching engagement with the lever.

The keyhole is located in the body portion of the plate presented toward the fettered prisoner, to prevent access to the keyhole by a key in one of the prisoner's hands.

The lever finger 6 is preferably provided with notches 20 having upwardly outwardly inclined faces 21, and the pawl has one or more teeth 22 adapted to engage in the notches of the lever to latch the lever against movement in one direction.

The upper end of the wall 17 in the figures is spaced from the wall 15 sufficiently to permit the toothed end of the key-operated pawl to move partly past the same. The key-receiving portion of the pawl is adapted to engage the inner edge of the wall 15 when the pawl teeth have been moved out of the path of the lever but before the ward of the key has moved past the pawl, as clearly shown in Fig. 2, for limiting retractive movement of the pawl. The pawl may thus be held by the key in retracted position to permit the lever to be revolved freely in either direction on its pivotal mounting, the structure avoiding possible location of the ward in the inaccessible recess behind the key-receiving end of the pawl.

The lever further includes a pair of arcuate clamping portions 23 and 24 having inner edge faces adapted to cooperate respectively with the seats 2 and 3 to form openings corresponding substantially to the contour of wrists or the like which the device is adapted to fetter. A web or flange 25 between the

clamps 23 and 24 extends between the walls 4 of the support when the lever is in fettering position.

The edges of the web and inner faces of 5 the clamps 23 and 24 merge to form with the inner edge faces of the seats a pair of oval openings having longitudinal bisectors inclined inwardly downwardly toward a vertical central line on the device in fettering 10 position in Fig. 1, whereby the wrists of the prisoner will incline upwardly outwardly from each other, the backs of the wrists being respectively adjacent the body of the support and the outer ends of the arms.

15 The seats 2 and 3 are substantially identical in dimensions and contour. In order to assure adjustment of the lever to wrists of various sizes, the clamping portion 23 has an inner edge face formed on a slightly longer 20 radius than that of the portion 24. The portion 23 obviously moves over a greater distance than the portion 24 when the lever is revolved. The portion 23, due to its greater length, will therefore effectually clamp one 25 large wrist when the other large wrist is clamped by the other portion. When relatively small wrists are to be fettered, the portion 23 will form an opening substantially equal to the opening formed by the 30 other portion when the latter has moved sufficiently to clamp one of the small wrists.

In assembling a device such as described above, a relatively small body is required to form a housing or lock case for the single 35 latching pawl and single locking arm of the lever, and cost of material and labor of construction are thus materially reduced, this being an important feature since most manacles are assembled by hand after the necessary 40 elements are stamped out of steel sheets by dies.

A considerable saving in moving and fixed parts and labor of assembly is thus effected over manacles in which latching means must be provided for two wrist-clamping levers.

45 Manacles constructed as described occupy relatively small space, and may be carried in closed and locked position without hazard of accidental opening.

50 When the manacles are to be employed for fettering, the palms of the prisoner are brought together, and the device applied in one swinging operation, the pressure of the lever portions against the wrists causing the 55 lever to revolve and admit the wrists to the seats, incidentally displacing the pawl against the influence of the spring.

The lever is freely rotatable on the pivot pin between the arms of the support, and 60 will swing in a complete circle to engage the clamping portions with the wrists. The ratchet teeth on the outside circle of the free curved outer end portion of the lever engage the pawl, to effect latching of the lever, and 65 lock both wrists coincidently to the support.

Since the back of one wrist is presented to the lock, the prisoner will be unable to twist his hands to reach the keyhole with a key or pick in the hand fetter by the clamping portion 23, and said hand will obstruct the other hand, the picking of the lock thus being effectually prevented.

70 The wall 17 which partly closes the inner edge of the case extends closely adjacent the path of the curved toothed end of the lever, and prevents insertion of a pick to the pawl for tampering therewith.

75 When the manacles are to be removed, the key is inserted in the recess of the body, and slight turning thereof displaces the pawl, to free the lever therefrom. The rigid lever may then be retractively rotated to free the wrists, one motion unlocking both clamps, and a second motion moving both clamps from the wrists.

80 What I claim and desire to secure by Letters Patent is:

1. In a device of the character described, a body comprising spaced plates having arcuate portions forming wrist-receiving seats and a rigid lever pivotally mounted on the body to swing between the plates and having clamping portions provided with arcuate faces cooperating with said seats to form wrist-receiving openings.

90 2. In a device of the character described, a support comprising spaced plates including a body forming a lock case and having an arm including arcuate portions forming wrist-receiving seats, a rigid lever pivotally mounted on the outer end of the arm to swing between the plates and having clamping portions provided with arcuate faces cooperating with said seats to fetter wrists or the like coincidently, and means in the case for latching the lever against movement in one direction.

95 3. In a device of the character described, a support comprising spaced plates including body portions forming a case and arms having arcuate portions forming wrist-receiving seats, a rigid lever having an outer end pivotally mounted on the outer ends of the arms to swing between the arms and having clamp- 100 ing portions provided with arcuate faces co- 105 operating with said seats to clamp wrists thereto, and means in the case engageable with the free end of the lever for latching the lever in wrist clamping position against movement in unclamping direction.

110 4. In a device of the character described, a support comprising spaced plates and including a body and spaced arms formed to provide laterally spaced seats having arcuate edges, a lever having arcuate clamping portions pivoted to the outer ends of the arms and revolvable between the arms, the clamping portions cooperating with the respective seats to fetter the wrists of the person to whom the device is applied, the free end of 115 120 125 130

the lever being movable adjacent the body and means in the body for locking the lever against movement in unclamping direction, the clamping portion adjacent the free end of the lever being formed on a longer radius than the portion adjacent the pivotal mounting of the lever for adjusting the lever to wrists of various sizes.

In testimony whereof I affix my signature,

10 STELLA FRANCES GILL.
